United States Patent Office

Des. 177,455
Patented Apr. 10, 1956

177,455

SOFA

Stanley G. Young, Long Beach, Calif., assignor to Frank Bros., Inc., Long Beach, Calif., a corporation of California

Application July 11, 1955, Serial No. 36,915

Term of patent 14 years

(Cl. D15—11)

F16.2

FIG. 3

FIG. 4

Figure 1 is a side perspective view of a sofa embodying my new design;

Figure 2 is a side elevational view of said sofa;

Figure 3 is a front perspective of said sofa; and

Figure 4 is a top plan of said sofa.

I claim:

The ornamental design for a sofa, substantially as shown.

References Cited in the file of this patent

UNITED STATES PATENTS

D. 174,929 Spound _____ June 7, 1955
D. 175,131 Rutter _____ July 12, 1955

OTHER REFERENCES

Interiors, September 1953, page 111, chair at lower left of page.

Designs, March 1954, No. 63, page 17, center chair of three at bottom of page.